UNITED STATES PATENT OFFICE.

WILLIAM A. PIKE, OF NEW YORK, N. Y.

DESIGN FOR AN INKSTAND.

SPECIFICATION forming part of Design No. 16,453, dated January 5, 1886

Application filed December 3, 1885. Serial No. 184,648. Term of patent 7 years.

To all whom it may concern:

Be it known that I, WILLIAM A. PIKE, a citizen of the United States, residing at New York city, New York, have invented a certain new Design for Inkstands; and I do declare the following to be a full, clear, and exact description of the invention, such as will enable others skilled in the art to which it appertains to make and use the same, reference being had to the accompanying drawing, and to the letters and figures marked thereon, which form part of this specification.

The invention relates to designs for inkstands; and the novelty consists in the features illustrated in the accompanying drawing, and hereinafter described.

The design consists in the representation of an owl's head. The ears display a filamentous filling.

Referring to the drawing, *a* designates the neck and shoulders, which comprise the wider part or base. *b* designates the beak, *c* the eyes, and *d* the ears. The ears display a filamentous filling, *f*.

I claim—

The design for an inkstand herein shown and described, consisting of the representation of an owl's head having ears displaying a filamentous filling, as set forth.

In testimony whereof I affix my signature in presence of two witnesses.

WILLIAM A. PIKE.
